UNITED STATES PATENT OFFICE.

C. L. REHN, OF PHILADELPHIA, PENNSYLVANIA, ASSIGNOR TO J. LUCAS & CO., OF SAME PLACE.

FASTENING FOR METALLIC KEGS.

Specification forming part of Letters Patent No. **30,350**, dated October 9, 1860.

To all whom it may concern:

Be it known that I, CASPAR L. REHN, of the city of Philadelphia and State of Pennsylvania, have invented a new and Improved Fastener for Metallic Kegs; and I do hereby declare the following to be a full, clear, and exact description of the same, reference being had to the accompanying drawings, and to the letters of reference marked thereon.

My invention relates to the peculiar construction of a metal bar forming a fastener for securing the lids of metallic kegs, such as are used for containing mixed paints, &c., and the said fastener consists of a plate having two projecting arms, one or both of which has a rounded end, both having notches, and the whole being otherwise constructed as described hereinafter, for attachment to and detachment from certain staples on the edge of the keg by the method hereinafter explained.

In order to enable others to make and use my invention, I will now proceed to describe its construction and operation.

On reference to the accompanying drawings, which form a part of this specification, Figures 1 and 2 are sectional views of part of the body with the cover of a metallic keg illustrating my improved fastening for the same; Fig. 3, a plan view; Fig. 4, a transverse section of the fastening-bar, on the line 1, 2, Fig. 3; Fig. 5, a view of one of the staples for receiving the ends of the fastening-bar.

A represents the upper end of a metallic keg, such as is used for containing mixed paints, &c., the edge of the keg being furnished on the inside with the annular stiffening-rib *a*. B is the cover, consisting of a metal disk having on its outer edge an annular flange, *b*, fitting over the edge of the keg; the cover being made of tinned plate or other material capable of yielding under pressure, and recovering its original position after the removal of that pressure. Near the upper edge, and on opposite sides of the keg, are secured the staples D and D', having openings for receiving the notched ends of the fastener E, which consists of an annular plate, *f*, with two projecting arms, *e* and *e'*, as best observed on reference to the plan view, Fig. 3, the under side of the annular portion of the fastener projecting below the under side of the arms,

as seen in the sectional view, Figs. 1 and 2. After the cover has been fitted over the edge of the keg one of the arms *e* of the fastener is inserted into the opening of one of the staples D, the end of the arm projecting through its staple, as seen in Fig. 1, and this to such an extent that when the fastener is depressed the opposite arm *e'* will assume that position in respect to the opposite staple D' represented in red lines, Fig. 1. By thus depressing the fastener its annular portion *f* will bear on the cover B, causing the same to yield.

It will be observed that the ends of both arms are notched at *y* and rounded at *x*. As seen in Fig. 1, the rounded arm *e'* is presented to the opening in the staple D', so that on imparting a smart blow to the end of the opposite arm *e* the end of the arm *e'* will pass directly into the opening of the staple, its passage being facilitated by its rounded end. The fastener is now secured to its place, the notch of one arm having caught hold of one staple and the notch of the other arm onto the opposite staple, as seen in Fig. 2. The tendency of the cover to recoil from its bent position serves the double purpose of maintaining the fastener in its proper place and keeping the lid tight on the edge of the keg. When the cover has to be removed, one arm of the fastener is depressed to an extent sufficient to remove its notch from its hold on the staple, when it may be pushed back through the opening of the said staple to the position shown in red lines, Fig. 1, after which the fastener is readily removed, thus allowing for the removal of the cover.

As the fastener forms no permanent part of the keg, but is detachable therefrom, it may be readily applied to any other keg, that from which it has been removed being used as an ordinary paint-pot by connecting the usual handle to the staples D and D'.

I wish it to be understood that I do not claim, broadly, the employment of a rod or bar with its end held in staples attached to the mouth of a vessel for the purpose of confining the cover, several modifications of such a device having been heretofore used; but

I limit my claim to and desire to secure Letters Patent for—

The fastener E, composed of the plate *f* and

its two arms, 'e' and 'e'', when one or both of the said arms have a rounded end, 'x', and each arm has a notch, 'y', and when the whole is otherwise constructed, as set forth, for attachment to and detachment from the staples D and D' on the edge of the keg by the method and for the purpose herein described.

In testimony whereof I have signed my name to this specification in the presence of two subscribing witnesses.

CASPAR L. REHN.
